SAFETY RAZOR AND BLADE

Hyman R. Segal, New York, N. Y.

Application October 3, 1931, Serial No. 566,619

4 Claims. (Cl. 30—12)

This invention relates to improvements in safety razors.

It is a primary object of the invention to provide a safety razor having devices for guiding and supporting the blade in its proper position on either the guard or the plate of the razor.

It is a further object of the invention to provide an improved safety razor blade which can be applied to safety razor frames having various configurations of blade supporting projections thereon.

It is a still further object to provide a safety razor frame which can be readily constructed and assembled and which will be more satisfactory in use than those heretofore constructed.

The above and other objects will appear more fully from the following description when considered in connection with the drawing in which:

Fig. 1 is a longitudinal sectional view through a safety razor illustrating one form which my invention may assume.

Fig. 2 is an outer face view of the guard and blade with the clamping plate removed, parts being broken away.

Fig. 3 is an inner face view of the clamping plate constructed in accordance with my invention.

Figs. 4, 5, 5a, 6 and 7 illustrate the application of the blade constructed in accordance with my invention to various styles of razor frames.

Referring to the details of the drawing, there is illustrated in Fig. 1 a razor comprising a handle 10 and a head 12, the illustration being of a two-piece razor wherein the guard and handle are formed of one-piece or are permanently attached together. The head 12 includes a guard 14 and a clamping plate 16 constructed to draw the shaving blade firmly against the guard.

The plate 16 is preferably constructed of a length so that it extends outwardly beyond the blade 18 as indicated at 19. The projecting end portion of the plate 16 may be rounded as shown so as to present no sharp surfaces and to reduce the thickness of the plate at the ends of the razor.

The central portions of the ends of the guard are formed with the recesses 15 to facilitate removal of the plate and blade therefrom. The ends of the guard are further cut away as indicated at 17 to form spaces for receiving any burrs or projections formed on the ends of the plate 16 intentionally or by accident.

The outer ends of the plate 16 are cut away on the underneath surface of the same as indicated at 16a so as to tend to prevent the formation of any burr extending below the underneath surface of the plate and into contact with the blade 36 or the guard 14.

The guard 14 may be formed with the surface projections 14a at the corners thereof, if desired, which projections receive corresponding recesses

in the corners of the clamping plate and of the blade, the projections 14a tending to prevent the formation of burrs on the guard 14 if it should be dropped to the floor, for example.

In accordance with the present invention there is provided an abutment which extends across the major portion of the head and which is formed in part on the outer face of the guard 14 and in part on the inner face of the plate 16. The abutment thus includes a projection 18 formed on the outer face of the guard 14 and the inwardly projecting lugs 20 formed on the inner face of the plate 16. The projections 18 and 20 together form a substantially continuous symmetrical abutment of the configuration illustrated in Figs. 2 and 3 for spacing the razor blade received between the plate and guard. The plate is formed with a recess for receiving the abutment 18 and the guard is formed with openings or recesses, preferably the former, as shown, for receiving the lugs 20.

The plate is constructed to be removable with respect to the razor frame proper and to this end is provided with an attachment shank 22 formed with a screw-threaded portion 23 for cooperation with the attachment nut and with a squared or other out-of-round portion 24 for guiding the same in relation to the guard. The shank 22 is constructed to be received in an opening 26 formed at the center of the guard, the opening 26 being squared or of other out-of-round configuration corresponding to the cross-section of the outer portion 24 of the shank. The opening 26 is formed as a continuation of the hollow interior 28 of the handle 10 and may be squared for a considerable portion of its length or only adjacent the guard as shown.

The attachment nut for receiving the screw-threaded shank 22 includes the internally threaded attachment stem 30 which is formed integrally with or permanently attached to the thumb piece 32 positioned at the inner end of the handle 10. The stem 30 and thumb piece 32 are more or less permanently attached to the handle 10 in a manner which will permit rotation of the stem and thumb piece with respect to the handle but which will prevent longitudinal movement of these parts except on the application of extreme pressure tending to separate them. This is accomplished by providing a bushing 34 loosely received on the stem 30 between the thumb piece 32 and a transverse securing pin 35, the bushing 34 being forced into the interior of the handle 10, and having a friction tight or press tight fit therein so that it can not be readily removed.

The blade 36 employed herein is formed with a central opening 38 corresponding to the outline of the abutment formed by the projection 18 and lugs 20. This opening is formed of the

especial design disclosed so that it can be readily fitted to most, if not all, of the known razor frames. The opening 38 as thus formed embodies a comparatively wide main central portion 5 of general rectangular configuration and having the outwardly bowed or elliptically curved side walls 39 (Fig. 4) terminating in the straight longitudinal portions 40 which are parallel with the major axis and cutting edges of the blade and 10 which in turn terminate in the angular (oblique) walls 41 which are continued in the walls forming the reduced tips 42 and disposed between said top walls and the walls 39. The angular portions 41 at either end are arranged substantially 15 at right-angles to one another as shown. The blade 36 may have the cut-away corners 44 for cooperation with the projections 14 described above. It will be understood that this construction is not essential and that the projections 14a and cut-away corners 44 may be 20 omitted.

A blade constructed in accordance with this invention will satisfactorily cooperate with a correspondingly shaped abutment as shown in 25 Figs. 1, 2 and 3. It will, however, coact equally satisfactorily with a plurality of other connections or abutments, as, for example, the circular studs 46 of Fig. 4, which engage the abutment surfaces 43, 41, or with the abutment 30 47 of oval design as shown in Fig. 5, which engage the abutment surfaces 38, 39, 48, 41, or with the abutment 51 of a well-known razor as illustrated in Fig. 5a, said abutment engaging the abutments 38 and 39 and having reduced end extensions 35 engaging the tips or recesses 42. Similarly, the blade 36 may be used in a razor formed with the abutment 48 of Fig. 6, wherein the abutment is of general S-formation. The blade may likewise be used with a razor having rectangular studs 50 as shown in Fig. 7, thus making it adaptable for use upon different razors the blades provided for use with which are ordinarily of arbitrary type and suitable for use with a particular razor only.

Having now described my invention, I claim:

1. In a safety razor, a guard, and a clamping plate constructed for attachment to said guard and cooperating therewith to clamp a blade therebetween, said guard having projections at its corners to engage recesses at opposite sides of the ends of a blade, each end of the guard being concavely cut away between the projections to form a finger recess to expose the end of the blade, the said corner projections of the guard and the end edges of the plate having their opposed inner surfaces provided with beveled divergent faces lying on opposite sides of and forming V-shaped recesses housing the end edges of the clamped blade adjacent to the ends of their cutting edges.

2. In a safety razor, a body part formed with a hollow handle, a clamping plate, an attachment shank thereon and means for attaching said plate to said body part comprising a finger-piece, an attachment stem carried thereby and rotatable within the handle and having a detachable threaded engagement with said shank, a bushing sleeve at the inner end of the handle abutting at its outer end against the finger-piece and forming an annular bearing member in which the said attachment stem is freely rotatable, the peripheral portion of said bushing having a friction fit

within said handle adapting it to maintain its position therein while being withdrawable under a strong pull, and a retaining member within the hollow handle passing through the stem and engaging the end of the bushing and forming a coupling connection between the stem and bushing whereby the latter may be withdrawn from the handle by a pull upon the stem.

3. In a safety razor, a guard of generally oblong rectangular form having a blade clamping face provided with a central, longitudinally extending abutment projecting outwardly beyond said clamping face, receiving openings lying at the ends of said abutment and between the same and the ends of the guard, and a non-circular opening extending centrally through the guard and abutment, said recesses being of a form tapering toward the ends of the guard to provide straight end portions and obliquely inclined shoulders between the same and the ends of the abutment, a clamping plate having a clamping face for clamping a blade against the face of the guard and provided with a recess to receive said abutment on the guard and projections at the ends of said recess of a conformation to engage the openings in the guard and the said inclined shoulders at the inner ends thereof, the said interengaging portions of the guard and plate forming blade guiding surfaces partly on the guard and partly on the plate and coacting with the clamping faces thereof to form substantially continuous blade engaging surfaces from end edge to end edge and side edge to side edge of the plate, a blade formed with an opening of substantially the same contour as said abutment and 35 projections, whereby the guard, plate and blade are provided with undulatory engaging surfaces along their longitudinal edges from end to end thereof, a hollow handle fixed to the guard, an attaching shank fixed to the clamping plate 40 and having a non-circular portion slidably engaging the non-circular opening in the guard and terminating in a threaded circular portion extending into the handle, and a rotary stem journaled in the handle and having an internally 45 threaded portion engaging the threaded portion of the shank for detachably holding the guard and plate in blade clamping engagement.

4. In a safety razor, a guard, a clamping plate for clamping a blade between the same and the 50 guard, a hollow handle carrying the guard, an attachment stem carried by the plate and extending movably through the guard into the handle, a coacting threaded attachment stem engaging the first-named stem and extending at one end 55 through said hollow handle, a finger-piece mounted upon the projecting end of the second attachment stem and having a shoulder bearing against said end of the handle, a bushing sleeve forming a bearing for the outer end of the stem, 60 said sleeve being fitted with a friction press fit within the handle and abutting against the shoulder of the finger-piece, and a fastening connection within the handle passing through the attachment stem carrying the sleeve on the opposite side of the bushing from the finger-piece, and forming a connection whereby on uncoupling the attachment stems the bushing may be withdrawn by a forcible pull with the second-named attachment stem from the handle.
